SHUTTLE BOX FOR LOOMS

Latt J. Carter, Kannapolis, N. C.

Application March 14, 1950, Serial No. 149,580

4 Claims. (Cl. 139—183)

1

This invention relates to looms and more especially to an improved shuttle box therefor.

Shuttle boxes generally include a front box plate, a rear box plate and a rear binder. The proximate surfaces of the rear binder and the front box plate have heretofore been provided with a leather liner so as to frictionally hold a boxed shuttle between the front box plate and the binder and to protect the shuttle against wear and also to prevent wear of proximate surfaces of the binder, the rear box plate and the box front.

It is well known that the leather material used on the proximate faces of the front box plate and the binder become worn and otherwise damaged through the repeated impact of the shuttle as it enters and leaves the shuttle box thus requiring that these leather liners be replaced periodically. Also, in many instances the front surface of the back box plate and any other metallic wearing surfaces on the front box plate and the rear binder become scored thus requiring that they be discarded and, in many instances, causing damage to the shuttle.

It is, therefore, an object of this invention to provide a front box plate, a rear box plate and a shuttle box rear binder, the wearing surfaces of which are chromium plated so as to provide a closely grained or super-smooth finish to the surfaces thereof which are to be engaged by the movement of the shuttle into and out of the shuttle box. Since the chromium is substantially more wear resistant than the wearing surfaces of the usual shuttle box front and the rear box plate and the binder, the surfaces of the same, which are engaged by the shuttle, will not become scored with constant movement of the shuttle into and out of the shuttle box and, further, it is not necessary to provide a leather liner on the working surfaces of these parts as heretofore has been the case.

By chromium plating the working surfaces of the shuttle box front plate, rear plate and the binder, it is possible to salvage parts which heretofore have been discarded as being of no further use since the grooves or any other imperfections caused in the working surfaces of these parts may be filled with suitable metal and then made smooth by the chromium plating of these surfaces.

Some of the objects of the invention having been stated, other objects will appear as the description proceeds, when taken in connection with the accompanying drawings, in which—

Figure 1 is a top plan view of a shuttle box and a portion of one end of a lay of a loom;

2

Figure 2 is a fragmentary front elevation of a portion of the shuttle box shown in Figure 1;

Figure 3 is an isometric view looking at the opposite side, the outer end and top surfaces of the shuttle box front shown in Figure 2;

Figure 4 is an enlarged vertical sectional view taken substantially along the line 4—4 in Figure 3;

Figure 5 is an enlarged vertical sectional view taken substantially along the line 5—5 in Figure 3;

Figure 6 is a rear elevation of the shuttle box shown in Figure 1 and showing the binder and back box plate associated therewith;

15 Figure 7 is an enlarged isometric view looking up at the lower surfaces of the back box plate shown in Figures 1 and 6 and also showing the inner end and the front surfaces of the back box plate extension shown in Figure 6;

20 Figure 8 is an enlarged vertical sectional view taken substantially along the line 8—8 in Figure 7;

Figure 9 is an enlarged isometric view looking at the lower and front surfaces of the back binder 25 shown in Figures 1 and 6 and also looking at the opposite side of the back binder from that shown in Figure 6;

30 Figures 10 and 11 are vertical sectional views taken along the lines 10—10 and 11—11, respectively, in Figure 9 and showing the chromium plating applied to the inner or front surface of the back binder shown in Figure 9.

35 Referring more specifically to the drawings, the numeral 10 indicates an oscillatable lay of the loom which is usually supported on swords, not shown, and a rear box plate, designated broadly at 11, is also adapted to be secured to one of the swords, not shown, as by a screw 12 which is shown in cross-section in Figure 6 and which

40 penetrates a hole 9 in the back box plate 11. The box plate 11 is a part of a shuttle box broadly designated at 13. The shuttle box shown is of a type adapted to be associated with a filling replenishing mechanism of a type shown in U. S. Patent No. 1,552,388 of September 1, 1925. However, the scope of this invention is not confined to a shuttle box of the type described nor to a so-called filling-replenishing loom.

45 The shuttle box 13 includes a lay end 14 having a longitudinally extending opening 15 therein through which an expelled bobbin is adapted to pass as a replenishing bobbin 16 is moved into a shuttle 17 upon the shuttle 17 being boxed in the shuttle box 15 between a rear binder 20 and 50 a box front or front box plate broadly designated

at 21. The front box plate 21 is secured, as by screws 23 to the upper surface of the lay end 14. A weft yarn 17a extends from the eye of the shuttle 17 to the proximate selvage of the cloth, not shown, and the box front 21 is provided with a groove 22 for reception of the yarn as it extends from the eye of the boxed shuttle 17 to the selvage of the cloth. The shuttle box front 21 will be later described in detail.

The loom is also provided with a conventional protector rod 25 which is oscillatably mounted in bearings 26, only one of which is shown in Figure 6, secured by bolts 27 to the rear surface of the lay 10.

As the shuttle 17 is thrown into the shuttle box 13, its outer end engages the usual picker 18 disposed on the upper end of a picker stick 19.

The protector rod 25 extends beyond the bearing member 26, in Figure 6, and has the lower end of a dagger finger hub 30 fixedly mounted thereon as by a screw 31. The dagger finger hub 30 has a dagger finger 31 threadably penetrating the same and this dagger finger 31 is secured in the dagger finger hub 30 by lock nuts 32 and 33 (Figure 1).

The dagger finger 31 is adapted to engage a pad 34, usually of leather, secured as by a screw 35 (Figure 11), to the rear surface and at the inner end of the rear binder 20. The conventional protector rod 25 has conventional spring means, not shown, so as to normally urge the dagger finger 31 forwardly which will, in turn, urge the rear binder 20 forwardly at its free end, the left-hand end thereof being pivotally mounted, as at 36 on the lay end 14. The bolt 36 also slidably penetrates a back box plate extension 40 which is an integral part of the back box plate 11.

It will be observed in Figure 9 that the back binder 20 has a sleeve or bushing 41 extending therethrough which is slightly longer than the vertical height of the corresponding portion of the back binder 20 so as to permit oscillation of the back binder 20 between the box back extension 40 and a washer 39 resting on the lay end 14 and which is also slidably penetrated by the bolt 36.

The back binder 20 is restricted at its free end, as at 42, and it is this restricted portion 42 to which the pressure pad 34 is secured by the screw 35. The lower surface of this restricted portion 42 is adapted to slidably engage the upper surface of a tongue 43 integral with a vertically disposed plate portion 44 of the back box plate 11. The back box plate 11 also has a horizontally disposed inwardly and upwardly curved flat portion 45 which merges with the extension 40 and a liner 46, of leather or other friction material, is secured, as by counter-sunk screws 47, to the lower surface of the back box plate extension 40 and extends along the lower surface of the flat portion 45, this friction material being curved back over the inner free end of the horizontally disposed flat portion 45 and being secured to the upper surface thereof as by a screw 50 (Figure 1).

Now, referring again to the front box plate 21, this front box plate 21 may be of any desired construction and, in the present instance, the front box plate 21 comprises an outer end portion 52. The outer end portion 52 has a suitable opening 53 therethrough which is provided for reception of the usual type of thread cutter such as is shown in United States Patent Number 2,203,560 of January 21, 1936. The shuttle box front 21 also has a longitudinally extending slot 54 therein, which curves upwardly and toward the inner end, indicated at 55, of the shuttle box

front 21. This slot 54 defines an upper longitudinally extending portion 56 and a lower portion 57, the lower portion 57 merging with the inner end portion 55. The groove 22, heretofore described, extends along the inner or rear surface of the inner end portion 55 of the shuttle box front 21.

A relatively short liner 60, preferably of leather, is preferably secured to the inner or rear surface of the inner end portion 55 of the shuttle box front 21 and the inner end portion 55 has a slot 61 therethrough through which a portion 62 of the liner 60 extends, this portion 62 being bent or curved back upon itself on the opposite side of the inner end portion 55 of the shuttle box 15 21 and being penetrated by a screw 63 which is threadably embedded in the inner end portion 55 of the shuttle box 21 for securing the liner 60 to the inner surface thereof. This liner 60 also 20 has a groove or depression 64 on the inner or rear surface thereof which coincides with the groove 22 in the rear or inner surface of the shuttle box front 21 (Figure 5). The liner 60 serves to prevent the shuttle 17 from rebounding upon being thrown into the shuttle box.

The inner end of the liner 60 extends around the innermost end 55 of the shuttle box front 21 and is secured, as by a screw 65 (Figure 2), to the inner end of the inner portion 55.

It is to be noted in Figures 2 and 3 that the inner face of the box front 21 from the slot 61 to the innermost end of the box front is more remote from the path of the shuttle than the remainder of the inner face of the box front so as to prevent the leather liner 60 from projecting too close to the path of the shuttle.

The upper longitudinally extending portion 56 of the shuttle box front 21 has the usual forwardly projecting thread catcher 67 thereon, the inner end portion 55 of the shuttle box front 21 also having a similar projection 70 thereon, these projections 67 and 70 being integral with the shuttle box front 21 and which are conveniently provided for engaging a new filling as the lay 10 moves forwardly at the first pick movement following a bobbin transfer operation.

The structure heretofore described is that of a typical shuttle box and the primary object of this invention is to provide means for extending the useful life of those parts which are engaged by the shuttle 17 and to also extend the period of usefulness of the shuttle. Referring to Figures 4, 8, 10 and 11, it will be observed that a greatly exaggerated thickness of chromium plating is applied to certain surfaces on the front box plate 21, the back box plate 11 and the back binder 20. The actual thickness of the chromium plating is approximately $\frac{1}{1000}$ of an inch. This chromium plating is applied in the usual manner of electrolysis.

The chromium plated surfaces of the shuttle box front 21 are the inner surface indicated at C-1 and the upper surface indicated at C-2. The so-called inner surface of the shuttle box front 21 includes the inner surfaces of the upper end portion 52, the inner end portion 55, with the exception of the area covered by the liner 60, and the inner surfaces of the longitudinally extending portions 56 and 57. The upper surfaces, which have the chromium plating C-2 thereon include the upper surfaces of the outer and inner end portions 52 and 55 and the upper surface of the longitudinally extending portion 56 as well as the projections 67 and 70.

In Figures 7 and 8, there is shown the surface

of the back box plate 11 which is chromium plated surface being indicated at C-3 and which is the front surface of the vertically disposed portion 44 and which is engaged by the side of the shuttle 17 remote from the side which engages the inner surface of the shuttle box front 21. This surface C-3 of the vertically disposed portion 44 of the back box plate 11, in Figures 7 and 8, also has approximately $\frac{5}{1000}$ inch thickness of chromium plating applied thereto although this thickness is exaggerated in Figure 8.

Now, referring to Figures 9 and 11, the front surface of the rear binder 20 is also chromium plated, this chromium plated surface being indicated at C-5, the showing in Figures 10 and 11 being illustrative of the fact that the chromium plated surface C-5 extends throughout the length of the rear binder 20 although, due to the curvature of the front surface of the rear binder 20, the rear surface of the shuttle 17 will engage the portion of the front surface C-3 of the rear binder 20 from a point intermediate the ends thereof to a point adjacent the sleeve 41.

It is thus seen that I have provided an improved shuttle box structure wherein the wearing surfaces of the shuttle box front 21, the back box plate 11 and the back binder 20 are chromium plated thus eliminating the cause of many loom stoppages due to the very smooth surface which is possible as a result of this chromium plating being applied to the working surfaces of these parts. By chromium plating these working surfaces, it eliminates the dimensional changes which usually take place in the ordinary types of wood back binders due to humidity and also eliminates the appearance of "jerked-ends" due to the surface of the leather being rough or having small projections thereon which might snag the weft yarns.

The chromium plating of the working surfaces of these parts of the shuttle box also decreases the cost of operation of the looms inasmuch as it will not be necessary for an operator to apply leather to the back binder or to the shuttle box front. This will also substantially increase the useful life of the shuttle 17 due to the reduction of friction since it is well known that the smooth surface caused by the chromium plating will

greatly reduce friction as the shuttle leaves and enters the shuttle box as compared to the shuttle entering and leaving a shuttle box wherein leather or a similar material is applied to the working surfaces of the back binder 20 and the shuttle box 21.

In the drawings and specification there has been set forth a preferred embodiment of the invention, and although specific terms are employed, they are used in a generic and descriptive sense only, and not for purposes of limitation, the scope of the invention being defined in the claims.

I claim:

15. 1. In a shuttle box having a box front and a rear binder and also having a back box plate for reception of a shuttle, the inner face of the box front which is nearest the path of the shuttle being recessed at its inner end for reception of a liner and the remainder of the inner face of the box front being chromium plated.
20. 2. In a loom having a shuttle box provided with a box front having a surface adapted to be engaged by a shuttle when boxed, the innermost end of said surface being recessed for reception of a liner and the remaining portion of said surface being plated with chromium.
25. 3. A shuttle box front having its inner surface provided with a depression near the inner end of the box front, a liner disposed in said depression, and the remainder of the inner surface of the box front being chromium plated.
30. 4. A shuttle box front having its inner surface provided with a depression near the inner end of the box front, a liner disposed in said depression, and the remainder of the inner surface of the box front being plated with a hard non-corrosive metal.

LATT J. CARTER.
